UNITED STATES PATENT OFFICE

144,037

DESIGN FOR A TRAFFIC LINE MARKING STUD

Albert Edward Bredin Crawford, London, England

Application April 6, 1945, Serial No. 118,886
In Great Britain January 9, 1945

Term of patent 14 years

(Cl. D72—1)

To all whom it may concern:

Be it known that I, Albert Edward Bredin Crawford, a subject of the King of Great Britain and Ireland, residing at London, England, have invented a new, original, and ornamental Design for a Traffic Line Marking Stud, of which the following is a specification, reference being had to the accompanying drawing, forming part hereof.

Figure 1 is a perspective view of a traffic line marking stud showing my new design.

Figure 2 is a plan view.

Figure 3 is a side elevation, and

Figure 4 is a front elevation.

I claim:

The ornamental design for a traffic line marking stud, as shown.

ALBERT EDWARD BREDIN CRAWFORD.
